ABSTRACT OF THE DISCLOSURE

This disclosure relates to a special mold dumping assembly enabling a combination of low profile, simplified construction with a dumping platform that tilts at its end. A mold car is moved from a stationary feeding track to the platform which is rotated upwardly to dump the load from the car. After the car has been dumped, the platform rotates about the axis downwardly to deliver the empty car to a stationary return track which is positioned beneath the feeding track, and the platform then returns to its original position.

The platform or dumping track is moved between positions by a specially arranged and cooperative fluid pressure assembly comprising a pair of cylinders attached directly to each other and positioned in side by side but oppositely oriented relationship. One cylinder has its piston rod attached to the platform at a point spaced from the pivot point, while the second cylinder has its piston rod attached to a fixed pivot mount. Controlled separate and cooperative actuation of the cylinders shifts the platform from the original position to the dumping position, from the dumping position to the car return position, and from the car return position back to the original position.

This invention relates to the dumping of molds positioned on wheeled vehicles. In one of its aspects it relates to a mold dumping assembly wherein a rotatable platform is rotated from a substantially horizontal first position about an angle in a first direction to a dumping position, about an angle in a second direction to a discharge position and back to the original first position by a fluid pressure means comprising a first fluid cylinder with an extendible piston rod attached to the platform at a point spaced from the axis of rotation, and a second fluid cylinder attached to the first cylinder having an extendible piston rod attached to a fixed pivot point.

In another of its aspects the invention relates to a mold dumping assembly as has been hereinbefore described wherein the first and second cylinders are in side by side relationship.

A variety of mold dump mechanisms have been devised over the last several decades. The mechanisms employ a tiltable track section mounted on a transverse pivot axis. Such a track section is normally cooperative with an upper track along which the full mold rides on a carrier or car, and cooperative with a lower track along which the empty mold car rides. Due to the economic necessity of automating foundry equipment as much as possible, even in small and medium size foundries, emphasis has been placed on efforts to effect an automatic dumping mechanism that would receive the car from the upper track, tilt it in one direction to dump it, then tilt it in the opposite direction to send the car back along the lower track, and finally tilt back to the initial position to latch to the upper track. One type of mechanism for doing this is illustrated in U.S. Patent No. 2,830,716. While automating this series of operations would seem relatively simple, and while the apparatus disclosed in the above identified patent does operate, in every day foundry practice, continued dependable performance of such automated

2

equipment does not always occur due to particular problems occurring in foundries. Particularly, the electrical limit switches, solenoid valve actuators, and signaling devices employed to control the power actuation of the dumping mechanism sooner or later become inoperative or undependable because of dust, sand, and other contaminants penetrating the electrical system.

One type of mold dumping device employs a pressure actuated piston in which a single pressure operated cylinder is employed to actuate the rotational movement of the tiltable track system. In this system, a latch mechanism must be employed to maintain the tiltable track in an aligned relationship with the upper track. With continued and frequent use of the device, there results breaking or wear of the latch due to the banging of the same against the cooperating locking portion of the upper track.

Some of the mold dumping devices use the weight of the mold to assist in the dumping operation. While this system is very helpful in the dumping operation, the overall system is more expensive to construct since the track must be high enough to dump the contents of the car into a container and conveyor. It is generally undesirable to dig a pit for the conveyor since the presence of ground water tends to contaminate the molding sand.

Thus, it is desirable to have a tiltable track section wherein the track rotates substantially about an end so that the upper track can be spaced reasonably close to the floor without having to dig a pit for the conveyor.

Granath 2,681,738 discloses a molding pallet dumping device in which a pair of fluid cylinders operate the dumping and transferring of the mold cars. This device, however, requires special separate linkage structures, a special expensive double tilt track assembly, and special arrangement of the fluid cylinders with this complex mechanism. The entire assembly is complex and costly.

I have now discovered a uniquely simplified, highly dependable mold dumping system whereby a tiltable track is power rotated substantially about one of its ends using a specially arranged and oriented pair of fluid cylinders capable of actuating the tiltable track without any extraneous complex, expensive mechanical linkages or double track apparatus.

By various aspects of this invention one or more of the following, or other objects, can be obtained.

It is an object of this invention to provide an improved system for dumping mold cars wherein a high dump is employed.

It is a further object of this invention to provide a fully power-driven system for dumping mold cars and the like wherein mechanical latches and linkages are avoided.

It is still a further object of this invention to provide a pneumatic system for dumping mold cars wherein a single mechanical arrangement is employed for rotating the tilting track.

It is still a further object of this invention to provide a control system for the operation of a fluid operated dumping system.

Other aspects, objects, and the several advantages of this invention are apparent to one skilled in the art from a study of this disclosure, the drawings, and the appended claims.

According to the invention, there is provided a mold dumping assembly including a stationary feeding track, a dumping track rotatable about a horizontal axis at one end thereof and a stationary return track, and power means to rotate the dumping track from a first position aligned with the feeding track to a second position in a dumping position, and to a third position wherein the dumping track is aligned with the return track. The power means employed in this invention comprises a first fluid pressure operated cylinder operably connected to the dumping track means and a second fluid pressure cylinder

rigidly attached to the first pressure cylinder and rotatably attached to a fixed point. The first and second fluid pressure cylinders are preferably positioned adjacent each other in side by side relationship.

The invention will now be described with reference to the accompanying drawings in which:

FIG. 1 is a side elevational view of a dumping track assembly according to the invention wherein the tiltable dumping track is aligned with the stationary feeding track;

FIG. 2 is a side elevational view of the assembly of FIG. 1 wherein the tiltable dumping track is in the dumping position;

FIG. 3 is a side elevational view of the assembly shown in FIGS. 1 and 2 wherein the tiltable dumping track is aligned with the return track;

FIG. 4 is an end elevational view of the assembly shown in FIGS. 1, 2 and 3 wherein the tiltable dumping track is aligned with the feed track; and

FIG. 5 is a schematic diagram of the pneumatic control system employed in the system shown in FIGS. 1 through 4.

Referring now to the drawings, a stationary horizontal feed track 2 is aligned with horizontal dumping track 4 which is rotatable substantially around one of the ends by pivoting on shaft 6. The tiltable track 4 is rotatable such that it can be aligned with stationary return track 8 (as shown in FIG. 3).

The stationary tracks 2 and 8 are supported by vertical support beams 10 and 12 which are connected by cross members 14, 16, 18, and 20, and also by a longitudinal support beam 44.

The tiltable track has an end stop member 24 adapted to be abutted by a wheel of a car positioned on the tiltable track. One end of the tiltable track 4 is supported by vertical member 22 and rotatable shaft 6. Spaced from this rotatable shaft 6 is a flange 26 through which the tiltable track 4 is attached to the power means. The flange 26 is rotatably attached through pin 28 to the end of a piston rod 30. A fluid operated cylinder 32 actuates the movement of piston rod 30. A second fluid operated cylinder 36 is attached through bolts 34 to fluid operated cylinder 32 in side by side relationship. Fluid cylinder 36 has a piston rod 38 which is rotatably attached to beam 45 through a flange 40 and a rod 42.

The downward rotation of track 4 is limited by stop 58 which is fastened to beam 44 (FIGS. 3 and 4).

A mold car 48 having wheels 50 and mold 49 is adapted to ride on the tracks 4 and 8.

A switch 52 is provided on the end of tiltable track 4 to initiate the movement of the track to the dumping position. This switch 52 is tripped by a loaded car as it reaches the end of the track. A second switch 54 is provided on support member 22 to initiate the movement of the tiltable track 4 to the return position. This switch is triggered by the end of the tiltable track 4 supporting member as it rotates to the position shown in FIG. 2. A third switch 56 is positioned on the top of stop 58. This switch 56 is tripped by tiltable track 4 as it reaches the return position. This switch initiates the return movement of the track 4 to the horizontal position. The switches can be levers with rollers or other similar cam followers on the ends thereof.

In operation, a mold car 48 with a mold 49 is advanced along track 2 until it reaches track 4 which is normally in the horizontal position in FIG. 1. When the car is positioned on track 4, switch 52 is tripped and the control system begins to function. In this first position, the piston rod 38 will be completely extended and the piston rod 30 will be completely retracted. The tripping of the switch 52 by the car actuates a pilot valve which allows fluid pressure to flow into cylinder 32 to cause piston rod 30 to extend to the position shown in FIG. 2 to tilt the track 4 so that the mold 49 slides from the car into a receiving container 46. The sand and the casting in

container 46 will be conveyed to a separating area for recovery of the sand for reuse and recovery of the cast product.

When the track 4 reaches its tilted position in the counterclockwise direction as shown in FIG. 2, switch 54 is actuated to exhaust the fluid from cylinders 32 and 36 thereby causing track 4 to tilt to its lowermost position as shown in FIG. 3. In this position, piston rods 38 and 30 will be completely retracted. As the track reaches this lowermost position, the mold car will roll down the track and onto the return track 8. When the track reaches the lowermost position, switch 56 will be tripped which after a short delay will cause the pressure to be supplied to cylinder 36 to extend piston rod 38. This extension of piston rod 38 will return the tiltable track 4 to the horizontal position shown in FIG. 1.

With the use of the invention, especially the embodiment shown in FIGS. 1 through 5, a high dump can be employed with a relatively simple mechanical arrangement. The whole system employs only a few moving parts. For example, the whole system employs only three points of rotation and no other mechanical linkages. Further, the side by side relationship of the piston cylinders permits a high dump of the tilting track and a relatively low positioning of the feed track 2 and return track 8. For example, with the use of the system shown in the drawings, the feed track can be about three feet above the floor, the return track 8 can be about 2½ feet above the floor and the container 46 can have its top portion only 2½ feet above the floor.

Referring now specifically to FIG. 5, the control system is operated by the fluid pressure source such as air which is passed through line 60, through branch line 62, line 64, valve 66, lines 68 or 70 to cylinder 32. Also, the fluid pressure is passed to line 76, valve 86, lines 78 or 82 to shoulder 34. Lines 68, 70, 78 and 82 all have speed control restrictions 67, 69, 80 and 84 respectively in the lines. Valve 66 is a spring biased, pilot operated valve. Valve 86 is a pilot operated valve.

Valve 66 is actuated by fluid pressure which passes through line 72, valve 53, line 73, valve 74 and line 75. Valve 74 is a detent pilot operated valve which is actuated when fluid pressure passes through valve 55 or valve 98. When the valve 74 is pushed to the left, any air pressure in line 73 will be blocked by a plug at 77. When valve 55 is opened, the fluid pressure will pass through line 88, line 94, through time delay 90, line 92 to shift valve 74 to the left. The air pressure will also pass through line 96 to pilot valve 86 to shift the valve 86 to the right.

When valve 98 is opened, the air pressure will pass through line 100, and through line 102 to the left side of pilot valve 74 to thereby shift the valve to the right. The air pressure will also pass through line 104, through time delay 106 to the right side of pilot valve 86 to shift that valve to the left.

In operation, valves 53, 55 and 98 are normally closed. In this normal condition, the tiltable track will be horizontal. Valve 74 will be positioned to the right as shown in the drawings; valve 66 will be positioned to the left; and valve 86 will be positioned to the left. When a car on a track trips switch 52, the valve 53 will open to allow air pressure to pass through line 73, valve 74, line 75, to pilot valve 66 to shift the valve 66 to the right. The air pressure will then pass through speed control restriction 69, line 70, to the lower end of cylinder 32 to cause the piston rod associated therewith to extend. This extension will rotate the tiltable track to the dumping position (FIG. 2).

As the track reaches the position shown in FIG. 2, the track will trip switch 54 to open valve 55. The air pressure will pass through line 88, valve 55, line 94, through time delay 90 to line 92 and the right side of pilot valve 74. This will cause the valve 74 to shift to the left, thereby venting the fluid in line 75. At this time, valve 53 will still be open but the air pressure will be blocked by plug 77.

The release of air in line 75 causes the valve 66 to shift to the left to permit the air pressure to pass through line 68 to the upper portion of cylinder 32, thereby retracting the cylinder. At the same time, the air pressure will be exhausted from the lower end of cylinder 32 through line 70 and speed control restriction 69.

Simultaneously, the air pressure will pass through line 96 to pilot on the left side of valve 86. This pressure will shift the valve 86 to the right thereby permitting fluid pressure to pass through speed control restriction 84, line 82 to the lower end of cylinder 34. This pressure will cause the piston rod of cylinder 34 to retract. At this same time, the air pressure in the upper end of cylinder 32 will be exhausted through line 78 and speed control restriction 80.

This retraction of the piston rods of cylinders 32 and 34 will cause the tiltable track to rotate to the return position (FIG. 3). In this return position, the track will actuate switch 56 to open valve 98. At this time, valves 53 and 55 will close. The air pressure then passes through line 100, valve 98, line 102 to the left side of pilot valve 74. This pressure on the left side of pilot valve 74 causes the valve to shift to the right. However, since no pressure is passing through line 53, there will be no change in valve 66. The air pressure also passes through line 104 through time delay 106 to the right side of pilot valve 86 to shift the core of valve 86 to the left after a suitable time delay. A time delay 90 also limits the rate of the exhausting of fluid from lines 92 and 96. The air pressure will then pass through line 76, line 78 to the upper end of cylinder 34 to cause the piston rod of that cylinder to be extended. This will raise the tiltable track back to the horizontal position. Therefore, after a short delay, the track will be raised from the return position to the horizontal position. The delay is provided to permit the car on the tiltable track to roll onto the return track.

The invention has been described with reference to an automatically controlled system, it is within the scope of the invention to provide a manually operated switch in place of switch 52. In this manner, the operation can be made semi-automatic with the operation of valve 53 to start the dumping operation being done manually.

Reasonable variation and modification are possible within the scope of the foregoing disclosure and the drawings without departing from the spirit of the invention.

I claim:

1. In a low profile mold dumping assembly including a stationary feeding track, a dumping track rotatable about a horizontal axis at one end thereof, a stationary return track, and a power means to rotate said dumping track from a first position aligned with said feeding track to a second position in a dumping position, and to a third position wherein said dumping track is aligned with said return track, the improvement which comprises a power apparatus formed of a first fluid pressure operated cylinder operably connected to said dumping track means, a second fluid pressure cylinder directly attached to said first fluid pressure cylinder, and rotatably attached to a fixed mount.

2. A mold dumping system according to claim 1 wherein said first and second cylinders are so arranged and powered that a piston rod of said first fluid pressure cylinder is retracted when said dumping track is in said first position, is extended when said dumping track is in said second position, and is retracted when said dumping track is in said third position, a piston rod of said second fluid pressure cylinder is extended when said dumping track is in said first position, is extended when said dumping track is in said second position, and is retracted when said dumping track is in said third position.

3. A mold dumping system according to claim 2 including a first switch means positioned to be activated by a car at the end of said dumping track, and operably associated with said first fluid pressure operated cylinder to cause it to be actuated to extend said piston rod when

said first switch means is activated by a car, a second switch means positioned for actuation by said dumping track actuates said first and second cylinder to retract said piston rods, and third switch means for actuating said second cylinder to extend said piston rod associated therewith when said dumping track is in said third position.

4. A mold dumping assembly according to claim 3 wherein there is further provided a timing means associated with said third switch means to delay the extending of said piston rod associated with said second cylinder to raise said dumping track when in said third position to permit said car to roll onto said return track.

5. A mold dumping assembly according to claim 1 wherein said first and second pressure operated cylinders are attached to each other in side by side relationship such that the direction of movement of piston rods associated with each of said first and second pressure operated cylinders is parallel, and the position of said piston rods are overlapping when both are retracted.

6. A mold dumping assembly according to claim 1 wherein said first and second cylinders are actuated by first and second valve means respectively;

a first switch means is operably associated with said first valve means and is located relative to said dumping track to be actuated by a car thereon, to thereby actuate said first valve means to extend a piston rod associated with said first cylinder when a car is received on said dumping track,
a second switch means is operably associated with said first and second valve means and located relative to said dumping track to actuate said first and second valve means to cause retraction of piston rods associated with said first and second cylinders when said dumping track reaches said second position,
a third switch means is operably associated with said dumping track and said second valve means to actuate said second valve means to extend said piston rod associated with said second cylinder when said dumping track reaches said third position.

7. A mold dumping assembly according to claim 6 wherein time delay means are operably associated with said third switch means to delay actuation of said second valve means for a predetermined time after said third switch is activated to permit a car on said dumping track to roll from said dumping track to said return track.

8. A mold dumping assembly according to claim 6 wherein said first valve means is a spring biased pilot operated valve,

a first conduit means is provided for supplying fluid pressure to the pilot end of said first valve means, said first switch means controls a first cam valve in said first conduit means, said first cam valve being adapted to connect said pilot end of said first valve means with a fluid pressure source or to vent pressure from said pilot end of said first valve.

9. A mold dumping assembly according to claim 8 wherein said second valve is a pilot operated valve, second and third conduit means are provided to supply fluid pressure to either end of said second valve for actuating said second valve, said second switch means operates a second cam valve in said second conduit means, said second cam valve being adapted to supply fluid pressure or to exhaust fluid pressure from one end of said second valve means,

said third switch means operates a third cam valve means in said third conduit means, said third cam valve being adapted to supply fluid pressure or to exhaust fluid pressure from the other end of said second valve means.

10. A mold dumping assembly according to claim 9 wherein a third pilot operated valve is provided in said first conduit means between said first cam valve and said

first valve means to exhaust fluid pressure in said pilot end of said first valve means when said second switch means is actuated,

said second conduit means communicates with one end of said third pilot operated valve such that said second cam valve controls the flow of fluid pressure to said one end of said third pilot valve,

said third conduit means communicates with another end of said third pilot operated valve such that said third cam valve controls the flow of fluid pressure to said other end of said third pilot operated valve to

5

return said third pilot operated valve to the condition whereby fluid pressure can be supplied to said pilot end of said first valve means.
